UNITED STATES PATENT OFFICE

157,379

GAS TANK CAP

George C. Knight, Detroit, Mich., assignor to
George C. Knight Company, Detroit, Mich., a
corporation of Michigan

Application July 28, 1948, Serial No. 147,806

Term of patent 3½ years

(Cl. D14—6)

To all whom it may concern:

Be it known that I, George C. Knight, a citizen of the United States, residing at Detroit, Wayne County, Michigan, have invented a new, original, and ornamental Design for Gas Tank Cap, of which the following is a specification, reference being had to the accompanying drawings, forming a part thereof, in which

Fig. 1 is a top plan view of a gas tank cap, showing my new design;

Fig. 2 is a side elevation;

Fig. 3 is a front end elevation, and

Fig. 4 is a rear end elevation thereof.

I claim:

The ornamental design for a gas tank cap, as shown.

GEORGE C. KNIGHT.
